DEVICE FOR SUPPORTING SHADE AND DRAPERY POLES

Filed Sept. 14, 1933

UNITED STATES PATENT OFFICE

2,050,507

DEVICE FOR SUPPORTING SHADE AND
DRAPEY POLES

Joseph Stracka, Cleveland, Ohio

Application September 14, 1933, Serial No. 689,408

5 Claims. (Cl. 248—265)

The present invention relates to holding shades and drapery in suspension opposite windows, doors and the like.

In the prior art, shade or drapery holding or suspension means have been used in the form of brackets which required a fastening means of some kind to hold the brackets in place. The disadvantage of such fastening means is that some tool is required to effect the fastening and, furthermore, considerable marring of window framing resulted in such fastening. This disadvantage is quite pronounced when changes are made in shades or draperies or when shades or draperies are moved from one window to another, or when wider or narrower shades or draperies are substituted and require different spacing of the brackets.

In the present invention, the brackets need no fastening means which would mar a window or door framing in any manner. No tools are needed to hold the bracket to a framing. The brackets have adjusting means thereon to locate shades or draperies in a desired location and to be adjusted to various widths of draperies.

Objects of the present invention are:

To provide a shade and drapery pole supporting device of simple structure.

To provide such a device with means whereby shade and drapery pole supporting brackets or members are adjustable on the device easily and conveniently and without requirement of tools.

To provide such a device with friction means to retain the shade and drapery pole supporting members in an adjusted position on the device.

To provide such a device with means to allow adjustment thereof relative to a support and to retain itself in any adjusted position thereof on said support by frictional engagement therewith and without requirement of tools.

To provide such a device with means to render the device as a whole adjustable on a support and to hold itself in such adjusted position by friction members on the device.

To provide such a device with means to render shade pole supporting members adjustable on the device independently of adjustment of drapery pole supporting members on the device.

To provide such a device with means to render drapery pole supporting members adjustable on the device independently of adjustment of shade pole supporting members on the device.

To provide such a device with an arm to support pole supporting members and to make this arm adjustable on the device and frictionally held thereon.

To provide such a device with friction means for each of the component parts thereof so that the device as a whole and each part thereof can be adjusted independently of the other parts thereof and so that each part thereof can be adjusted independently of the other parts and frictionally held in adjusted position without requirement of tools and without marring surface of the device nor of surface adjacent thereto.

Other objects will appear herein during the description of the device shown in the accompanying drawing, or will become obvious or apparent or will suggest themselves upon an inspection of this specification and the accompanying drawing.

The present invention is illustrated in the one type of device shown in the accompanying drawing, in which:

Fig. 1 is a perspective view of a device, embodying the present invention, and showing a vertically self supporting device with shade and drapery pole supporting members individually adjustable thereon and held in adjusted position by friction between members of the device.

Fig. 2 is a vertical section taken on the line 2—2 of Fig. 1 and shows the shade pole supporting bracket as mounted on the arm and the holes therein for the shade pole journals.

Fig. 3 is a vertical section taken on line 3—3 of Fig. 1 and shows the drapery pole supporting member as mounted on the arm.

Fig. 4 is a vertical section taken on line 4—4 of Fig. 1 and shows the locking member for a drapery pole supporting bracket as mounted on the drapery pole supporting member.

Fig. 5 is an enlarged sectional view of a preferred structure for frictionally retaining the pole supporting members on the arm.

Fig. 6 is an enlarged sectional view of a preferred structure for frictionally retaining the locking member on the drapery pole supporting member.

Fig. 7 is a horizontal sectional view of the end of the drapery pole supporting member and shows the abutments for a drapery pole supporting bracket and the locking member as related thereto.

Fig. 8 is a vertical section taken on line 8—8 of Fig. 1 and shows the form of the casing in one respect and the screw operated wedge mechanism therein.

Fig. 9 is a vertical section taken on the line 9—9 of Fig. 1 and shows the casing and the screw operated wedge mechanism at right angles to Fig. 8 and also shows the device as related to a vertical support.

Fig. 10 is a horizontal section taken on the line 10—10 of Fig. 9 and shows relations of the casing to the wedge mechanism and the open sides of the casing with the wedges extending through the same and in engagement on the vertical support.

Fig. 11 is a horizontal section taken on the line 11—11 of Fig. 9 and shows the relations between the casing and the wedge mechanism and the pins to retain the wedges in the casing.

Similar reference characters refer to similar parts throughout the views.

The device shown in the accompanying drawing for the purpose of illustrating the present invention consists principally of the self supporting element or member A, the arm B extending therefrom, the shade pole supporting member or bracket C on the arm, the drapery pole supporting member D also on the arm, and the locking member E for the drapery pole supporting bracket on the drapery pole supporting member.

The casing 10 for the element A is open at two opposite sides as shown. The operating screw F extends substantially through the middle of the casing and is confined, axially thereof, by the inner end of the head 12 abutting the outside of the end wall 13 of the casing and by the washer 14 with the end of the screw riveted thereover abutting the outside of the end wall 15 of the casing.

The screw F is shown with a right hand and a left hand threaded parts 16 and 17. One of the threaded parts is diametrically larger than the other for convenience of assembling of the device but the pitch of the two threads is preferably the same so that the below described wedges will remain central in the casing. The head 12 abuts the casing as is mentioned above and has the knurled part 18 on the outer end thereof for manual rotative manipulation of the screw and also has the driving slot 19 therein for rotative manipulation of the screw by means of a screw driver or the like when desired. Usually manual manipulation of the screw is sufficient to anchor the device but for heavy shades or draperies and when the fingers of the operator are quite or very weak it may be advisable to resort to a tool and the driving slot to retain the device in frictional self supporting contact with a vertical support.

The sleeve 20 is threaded onto the part 16 of the screw F and is driven into the wedge member 21. The wedge member 21 has two oppositely inclined faces 22 and 23 thereon.

The sleeve 24 is threaded onto the part 17 of the screw F and is driven into the wedge member 25 which also has two oppositely inclined faces 26 and 27. The widths of the wedge members 21 and 25, as seen in Fig. 9, is less near the inner end thereof than at the outer end. Preferably, the wedge members 21 and 25 fit loosely slidably between the walls 28 and 29 of the casing.

The contact member 30 fits loosely slidably between the walls 13, 15, 28 and 29 of the casing and has thereon two oppositely inclined faces 31 and 32 corresponding in angularity to the respective inclined faces on the wedge members 21 and 25.

The contact member 33 is a duplicate of the wedge member 30 and has the two oppositely inclined faces 34 and 35 corresponding in angularity to the respective inclined faces on the wedge members 21 and 25.

The highest points of the wedge members 30 and 33 are opposite each other and face toward

the inside of the casing. The inclined faces on the wedge members 21 and 25 are in contact on the inclined faces of the wedge members 30 and 33.

The slots 36 and 37 are cut through the walls 5 28 and 29 of the casing. The pin 38 is driven through the wedge member 30 and has the ends thereof extending through the slots 36 to retain the wedge member 30 in the casing but allow lateral movement thereof respective to the casing 10 so that the wedge member 30 can move inwardly and outwardly of the casing for engagement on and from the support 39 for the device.

The pin 40 is driven through the wedge member 33 and the ends of the pin extend through the 15 slots 37 to retain the wedge member 33 in the casing but to allow lateral movement thereof respective to the casing so that the wedge member 33 can move inwardly and outwardly of the casing for engagement on and from the support 20 39 for the device.

Fig. 9 shows quite clearly the above described relations between the casing and the wedge operating screw and the wedge members and the support for the device. 25

The wedge members may be made of metal or wood or rubber or a composition of rubber or other similar materials or composition of materials which has the property of adhering frictionally to other materials. It is preferred that 30 the support contacting faces 41 and 42 be serrated for better contact or be faced with a sheet of somewhat compressible material, either serrated or smooth on the outside, or be faced with a sheet of compressible material and serrated so 35 that the peaks of the serrations can be compressed to some extent at least to afford a better frictional engagement of the faces 41 and 42 on the support 39.

The device so far described is first held in a 40 desired position longitudinally of the usual window guiding groove provided in a framing, as the window framing 39 shown in the drawing. Rotation of the screw F in one direction moves the wedge members 21 and 25 toward each other 45 and thereby moves the wedge members 30 and 33 outwardly and into contact with or engagement on the walls 39a and 39b. The amount of power applied to the screw F determines the pressure of the wedge members 30 and 33 against the walls 50 39a and 39b. This frictional engagement is sufficient and can be made sufficient to hold or retain the entire device with shades and draperies supported thereon and does not mar or in any manner disfigure the supporting element and requires no tools for installation or for removal. 55

The guide or arm receiving bracket 43 is fastened onto the front of the casing near the bottom thereof and has the opening 44 through the same. When additional friction means is desired the 60 wall 45 may be formed with an inward curvature as indicated in dotted line in Fig. 8.

The arm B is rectangular and has parallel edges throughout its length and comprises the parts 46 and 47 angular with each other, preferably at 65 right angles as shown.

The free end 48 of the part 46 fits slidably into the opening 44 of the bracket 43 and is longitudinally adjustable therein so that the part 47 and mechanisms thereon can be adjusted nearer 70 to and further from the casing so that a drapery pole can be adjusted relative to a framing 39 indicated in the drawing in dotted lines.

In addition to the adjustment described in the just preceding paragraph, the arm may be re- 75

versed vertically so that the part 47 extends opposite to the position thereof shown in Fig. 1 or the end of the part 47 may be entered into the bracket 43.

5 The shade pole supporting bracket C has the sides thereof bent U shaped to embrace the vertical edges of the arm by means of the flanges 49 and 50 frictionally engaging the arm B. In the formation of the bracket C it is preferred that 10 the flanges 49 and 50 be formed with the inner ends thereof closer to the back thereof than the outer parts thereof as illustratively shown in Fig. 5. This structure utilizes resiliency of the material of the bracket to attain frictional contact 15 on the arm at all times since these inner ends will be forced outwardly when the bracket is on the arm and the natural tendency thereof is to revert back to their original positions.

The arm B, the bracket C, and the below described members D and E are preferably made 20 of material which has some resiliency therein so that parts thereof will remain in frictional contact on the parts attached to and thereby hold the arm and the bracket and the members in adjusted position relative to their supporting parts.

25 The bracket C has the outwardly bulging part 51 having the journal hole 52 in the outer wall thereof. This hole may be formed of the two angular branches as shown or with one round hole as is quite common and well known in brackets for shade pole support.

The drapery supporting member D is formed 30 similar to the bracket C and of the same sort of material for purposes similar to the bracket C. The end 53 of the member D extends over the end 35 of the part 47 of the arm B and the flanges 54 and 55 engage the arm frictionally to retain the member D thereon in adjusted position similar to the bracket C.

40 The vertical flange 56 is bent outwardly from the back wall of the member D to form the groove 56a to engage a vertical edge of a toe or similar means usually found on drapery supporting poles. The horizontal flange 57 is also bent outwardly 45 from the lower part of the member D in the same direction as the flange 56 to form the groove 57a to engage a horizontal edge of the mentioned toe.

The locking member E is formed similar to the bracket C and of the same sort of material and 50 for similar purposes. The flanges 58 and 59, preferably originally formed as seen in Fig. 6, engage the flanges 54 and 55 to frictionally engage the member E on the member D and thereby hold the member E in adjusted position on the member

55 D. The tongue 60 extends axially from the back part of the member E and is offset outwardly from the back wall thereof to provide the space 61. After a drapery pole is inserted into or between the flanges 56 and 57, the member E is slid 60 along the member D until the tongue 60 engages the toe of the drapery pole and thereby retains the pole in position.

The arm B is reversible either end for end or 65 side for side so that the same forms various means for adjusting the same relative to the casing or self supporting element A. The bracket C is slidable axially of the arm, either on the arm part 46 or 47, and is reversible thereon. This 70 adjusting means of the bracket C and the arm B affords a means for variously relating a shade pole to other structure.

The member D is also reversible on the arm B and can slide axially thereon and thereby form 75 a means for variously adjusting the member D

to meet various drapery poles and supports therefor.

The member E can slide on the member D to lock or retain a drapery pole on the member D.

Due to the resiliency in the material of the arm receiving bracket 43, the shade pole bracket C, and the members D and E, either one of these parts can be moved individually for adjustment and release themselves automatically and automatically retain themselves in adjusted position 10 after adjustment is made.

Throughout the device shown and described, frictional contact or engagement is provided so that the different members retain themselves automatically releasably in respective adjusted positions without requiring tools for such retaining and releasing and without marring a surface engaged thereby.

Without intention of limiting myself to the precise structure and arrangement of parts as shown 20 and described,

I claim:

1. In a device for supporting shade and drapery poles, a casing, friction members oppositely spaced in and movable relative to said casing, oppositely inclined faces on the opposing sides of each of said friction members, a screw axially confined in said casing and having a right hand and a left hand thread thereon, a wedge member threaded onto said right hand thread and 30 engaging two of said oppositely inclined faces, a wedge member threaded onto said left handed thread and engaging two of said inclined faces, and means for rotating said screw to move said friction members into frictional engagement with 35 a support and thereby support the device.

2. A device for supporting shade and drapery poles having a hollow casing open at both sides and adapted to be placed into a groove, opposite contact members in said casing and being extendable outwardly of said casing through the respective open sides of said casing for contact thereof on the side walls of the groove and each having the inner edge thereof beveled, a wedge member having opposite beveled edges to engage 45 with said beveled edges of said contact members, a screw axially of said groove and in threaded engagement with said wedge member to move both of said contact members outwardly of said casing and into contact on the side walls of said 50 groove.

3. A device for supporting shade and drapery poles relative to a groove, said device having a casing, rectangular in cross-section and open at each side, a contact member in each of the open 55 sides of said casing and having the contact surface thereof at least as large in area as the opening, both of said contact members opposing each other and having opposing bevel faces, a screw in said casing and held against axial movement 60 therein and having a right and left hand thread, a nut threaded onto each of said threads and each engaging both of the bevel faces of said contact members, means on an end of said screw, on the outside of said casing for rotating said screw 65 without limiting the possible number of revolutions thereof, and means for adjustably supporting shade and drapery poles on the front of said casing.

4. A device for supporting shade and drapery 70 poles relative to a groove having a casing, rectangular in cross-section and open at each side, a contact member in each of the open sides of said casing and having the contact surface thereof at least as large in area as the opening, both 75

of said contact members opposing each other and having opposing bevel faces, a screw in said casing and held against axial movement therein and having a right and left hand thread, a nut threaded onto each of said threads and each engaging both of the bevel faces of said contact members, and means on an end of said screw, on the outside of said casing for rotating said screw without limiting the possible number of revolutions thereof.

5. In a device for supporting shade and drapery poles, a casing, contact members in and movable relative to and guided in said casing, a

screw operated wedge means to move said members to frictionally engage a support and thereby support the device and comprising a screw extending through said casing and having a right hand and a left hand thread thereon, a wedging member threaded onto said right hand thread, a wedging member threaded onto said left hand thread, each of said wedging members engaging both of said contact members to move the latter into frictional contact on said support upon rotation of said screw, and means on said screw to rotate the same completely about its axis.

JOSEPH STRACKA.
